(57) **CLAIM**

We claim the ornamental design for an electronic cigarette vaporizer, as shown and described.

DESCRIPTION

FIG. 1 is a top perspective view of an electronic cigarette vaporizer.

FIG. 2 is a front elevational view of the electronic cigarette vaporizer depicted in FIG. 1.

FIG. 3 is a rear elevational view of the electronic cigarette vaporizer depicted in FIG. 1.

FIG. 4 is a left side elevational view of the electronic cigarette vaporizer depicted in FIG. 1.

FIG. 5 is a right side elevational view of the electronic cigarette vaporizer depicted in FIG. 1.

FIG. 6 is a top plan view of the electronic cigarette vaporizer depicted in FIG. 1; and,

FIG. 7 is a bottom plan view of the electronic cigarette vaporizer depicted in FIG. 1.

The broken lines in the drawings illustrate portions of the electronic cigarette vaporizer that form no part of the claimed design.
